UNITED STATES PATENT OFFICE

2,366,574

BRIDGE CRANE

Ernest W. Taylor, Bay City, Mich., assignor to
 Industrial Brownhoist Corporation, Bay City,
 Mich.

Application September 10, 1943, Serial No. 501,879

5 Claims. (Cl. 212—6)

This invention relates to a combination bridge crane for handling materials of fragmentary classification, as well as general cargo, such as steel, heavy machinery, timbers and other similar items.

One of the prime objects of the invention is to design a crane comprising a structural bridge having an adjustable boom hingedly secured thereto, said boom when in lowered position, forming a horizontal extension of the bridge so that the bridge and boom can be utilized as a track, with a trolley and grab bucket arrangement operable thereon for transferring coal, ore, and similar fragmentary materials into or out of a boat, railroad car, or other receptacle, said boom being quickly and easily swung up so that it can be used as a conventional crane boom for handling a magnet, or general cargo, such as machinery, steel, and similar materials and items.

Another object is to design a mobile handling machine adapted for installation on a pier or other supporting structure, and by means of which extremely heavy loads can be handled and transferred from car to vessel or vice versa; said machine being readily movable to desired location so that it can operate, load, or unload materials as above described at any point along the pier.

A further object is to provide a supporting structure on which the crane is mounted including bins into which the unloaded material is dumped preparatory to transfer to the transfer cars spotted in position to receive it.

A further object still is to design a machine having transfer bins for transfer of bulk materials to cars which bins are of a size and shape to support the grab bucket when the machine is used as a conventional crane for loading or unloading general cargo.

With the above and other objects in view, the present invention consists in the combination and arrangement of parts, hereinafter more fully described, illustrated in the accompanying drawings, and more particularly pointed out in the appended claims, it being understood that changes may be made in the form, size, proportion, and minor details of construction, without departing from the spirit, or sacrificing any of the advantages of the invention.

- In the drawings:

Fig. 1 is an end elevational view of my bridge crane showing it mounted on a pier with a cargo vessel adjacent thereto, and also showing railroad trackage, transfer cars, etc., the solid lines

showing the machine using a grab bucket for handling friable materials, the broken lines showing the boom raised for use as a boom crane with the grab bucket stowed in the material bin, and in another position the bucket is shown at one end of the bridge track.

Fig. 2 is a fragmentary top plan view.

Fig. 3 is a fragmentary side elevational view illustrating the equalizing tracks, the boom etc. being omitted.

Fig. 4 is a diagrammatic view of the rope system used when boom is raised and the machine used for handling general cargo.

Fig. 5 is also a diagrammatic view illustrating the closing rope system when the machine is used for handling bulk cargo.

Fig. 6 is a similar view illustrating the shell ropes.

Fig. 7 is a diagrammatic view illustrating the trolley travel ropes.

Fig. 8 is a fragmentary plan view of the boom and trolley, parts being broken away to more clearly show the arrangement.

Fig. 9 is a transverse sectional view through the boom and trolley taken on the line 9—9 of Fig. 8.

The present invention is of the same general character shown in Patent No. 2,226,361 granted December 24, 1940, and in which a full revolving superstructure is employed, in that it can be utilized for handling fragmentary materials as well as general cargo.

In the accompanying drawings in which I have shown the preferred embodiment of my invention, the machine is shown installed on a pier where cargo vessels may be tied, this pier being of the type handling general cargo, either coal, ore, etc. or bulk materials such as machinery, steels, crates, and other large, long, or bulky items.

The most efficient and practical machine for handling heavy machinery, fabricated steel and similar items is a boom type machine, because the boom can be swung over the side of the supporting base and there are no legs or structural supports to interfere with the "work" as it is lifted and swung to load or unload.

It is also generally recognized that the most economical and fastest type of machine for handling bulk cargo is a rope system trolley, which system comprises a grab bucket with a straight line operation, the boom being swung down and utilized as a horizontally disposed extension of the bridge which spans the pier, the bridge and boom forming a track on which a conventional bucket is operated for transferring the material

from a vessel to bins, and thence to cars, or from cars to vessels, etc.

In general practice, work of this nature has required two separate and distinct machines with initial cost, separate operators and maintenance, but in my instant design, all of this work is done with a single combination machine, with the consequent saving in initial cost, time and labor, and maintenance, it being merely necessary to attach the grab bucket to the hoisting rope or ropes whenever it is necessary to handle bulk materials, and to place the bucket on the bin and use a cargo hook when handling general cargo.

Referring now to the drawings in which is shown a pier P provided with spaced apart tracks 12 to accommodate the wheels 13 of equalizing trucks 14, which support the handling machine C, said machine comprising a structural bridge 15, supported on legs 17 and 17 respectively. A hopper 18 is mounted on and forms a part of the leg 17 and this hopper is of suitable capacity to suit the work required.

The hopper 18 can be of any desired shape, and is equipped with a pivoted discharge chute 19, for discharging the material into transfer cars 20 as usual, said cars operating on standard gauge railroad tracks 21, or the materials can be dumped into bins B or truck hoppers K at any point beneath the bridge 15, or transferred from this area to vessel or cars as desired.

The power plant and handling mechanism is mounted in a housing H provided on the bridge, and an operator's cab S is mounted on the extension 22 so that a clear view of operations may be had, the operator being stationed therein to control the loading, dumping, and handling of the mechanism and cargo in general.

A mast 23 projects above the housing H, and sheaves 24 are mounted thereon to accommodate the various ropes as will be hereinafter described, said mast being suitably braced by structural members 25 as usual.

A structural boom 26 is hingedly connected to the bridge 15 at the point 27, and when the machine is handling general cargo, this boom is swung up to position as indicated in broken lines in Fig. 1 of the drawings, and in this position the boom is operable in exactly the same manner as the boom on a conventional crane.

When the machine is handling coal, ore, or other fragmentary material, the boom is disposed horizontally as shown in solid lines in Fig. 1, and is supported in this position by means of a boom hoist rope 28, which rope is wound on the drum 29 provided on the housing H, said rope leading thence over the sheave 24, thence around the sheave 30 providing adjacent the outer end of the boom, and thence being dead-ended to the upper end of the mast at 32.

A trolley T is mounted for travel on tracks 33 which form a part of the boom and bridge respectively, the structure being suitably braced to support a predetermined load, said trolley comprising a frame 34 provided with spaced apart axles 35 and 36 respectively, and on which the track engaging wheels 37 are journaled.

A suitable racking unit controls the trolley travel, and includes a drum 38 drivingly connected to a motor (not shown), oppositely wound cables 39 and 40 are anchored to this drum 38, the cable 39 leading over sheave 41 and thence being anchored to one end of the trolley frame. The cable 40 is wound in the opposite direction leading under idler sheave 42 towards the outer end of the boom, thence around sheave 43, and thence

being anchored to the opposite end of the trolley frame, this arrangement provides that rotation of the drum 38 in one direction draws the trolley towards the bridge, and in the opposite direction will draw it towards the outer end of the boom.

The hoisting unit is mounted in the housing H and includes winding drums 45 and 46, these drums being connected to motors (not shown), as usual, a rope 47 being anchored to and wound on the drum 45, thence leading up and over a sheave 48 provided on the mast, thence down and around sheave 49 on the boom, and thence around sheave 50 provided on the trolley, thence the rope leads around the bucket sheave 51 provided on the bucket R, thence up and over the sheave 52 and thence being dead-ended at 54.

The bucket closing rope system is illustrated in Fig. 5 of the drawings, the rope 55 being wound on drum 46, thence leading down and around sheaves 56 and 57, thence over sheave 58 provided on the outer end of the boom, and thence over sheave 59, thence down and around sheaves 60 and 61, thence up and over sheave 62, and thence being dead-ended at 63 as usual.

When the machine is used as a boom crane for handling machinery, crates, steel, and heavy bulky objects, the bucket is stowed on the bin 18 and as indicated in broken lines in Fig. 1 of the drawings, the trolley proper being secured on the bridge and is held in any approved manner.

The boom is mounted for swinging in exactly the same manner as is the boom on a conventional crane, the rope 64 being wound on the drum 65, thence leading up and over sheave 66, thence out and over sheave 67 provided on the end of the boom, thence leading down and around sheave 68 to which the cargo hook 69 is attached in the usual manner, thence the rope leads up and is dead-ended at 70, and it will be clearly obvious that the hook can be raised or lowered by controlling the direction of the drum 65.

In practice, with the boom in position as shown in solid lines in Fig. 1 of the drawings, the drum 38 is driven to traverse the trolley T on the trolley track and spot it over the hatch in the vessel V. The drum 45 is then actuated to pay out the rope 47 and lower the bucket onto the material to be transferred, and when the bucket is loaded, the drum 46 is actuated to wind the rope 55 and close the bucket, and the drums 45 and 46 are again actuated to hoist the bucket to position directly beneath the boom, as illustrated in solid lines in Fig. 1 of the drawings. The racking drum 38 is now actuated to pay out on the rope 39 and wind in on the rope 40 to traverse the trolley, with the bucket suspended therefrom, toward the bridge end of the machine and spot it over the receiving hopper 18, bin B, or truck hopper K as desired. The drum 46 is next released so that the rope is unwound and the bucket will open and discharge the contents into the bin, and when the chute 19 is down, the material will flow directly to railroad cars, and if the chute is raised as indicated in broken lines in Fig. 1, the material will be retained in the bin. This completes the cycle of operation which is successively repeated until the transfer of material is accomplished.

When it is desired to use the machine for handling general cargo, the bucket R is stowed on the bin 18, with the trolley T located and locked on the bridge 15. The machine is now ready for conversion to operation as a boom crane. The hoist drum 29 is first actuated to wind the boom hoist cable 27 and elevate the boom to a desired angle of inclination, as generally shown in broken

lines in Fig. 1 of the drawings, after which the auxiliary drum 65 is actuated to wind or pay out the rope 64 to raise or lower the cargo hook so that heavy objects, crates or machinery can be handled as desired.

The machine will handle any work ordinarily performed by a boom crane and is quickly convertible to a straight line machine, it will likewise be apparent that the bucket may be utilized to transfer materials either from stock pile or cars located beneath the bridge, or to a vessel or to other cars adjacent thereto.

From the foregoing description, it will be obvious that I have perfected a very simple, practical, and substantial cargo handling machine.

What I claim is:

1. A system of the character described comprising a mobile carriage mounted for travel on a pier or supporting structure, said carriage comprising a bridge with a track thereon, a boom pivots connected thereto and adapted in its horizontal position to serve as a track extension of the bridge track for traversing a trolley and bucket for the material being handled, and in elevated position to serve as a boom crane for handling a variety of materials, means on the bridge to accommodate the bucket when the machine is being used as a boom crane, and means for elevating said boom.

2. A material handling system of the class described comprising a mobile carriage mounted for travel on a pier and including a bridge, a boom forming an extension of said bridge, tracks on said boom and bridge for traversing a trolley and bucket for the material, said boom when in elevated position serving as boom crane for handling a variety of materials, and means for elevating said boom.

3. A system of the character described for handling materials of various kinds comprising, in

5 combination, a mobile bridge mounted for travel on a supporting structure and provided with a trolley track thereon, a trolley, a crane mounted on said bridge, a boom pivotally connected to said bridge and adapted when in horizontal position, to form a continuation of said trolley track, material bins provided on the bridge, tracks and transfer cars disposed between the wheeled bridge and the edge of the pier, said cars being adapted to receive the material from said bins, and means for traversing said trolley on said tracks.

4. A system of the character described for handling material of various classifications comprising, in combination, a mobile bridge mounted for longitudinal travel on a pier, said bridge being provided with trolley tracks thereon, a crane mounted on said bridge and including a track boom pivotally and adjustably connected to one end of the bridge, a trolley, tracks and transfer cars interposed between said bridge and the one edge of the pier, means for traversing said trolley on said bridge and boom, and an independent rope associated with said boom for handling general cargo.

5. A combination bridge crane of the class described for handling materials of various classifications comprising, in combination, a mobile bridge provided with spaced apart supporting legs mounted for travel on a supporting structure, tracks on said bridge, a boom hingedly connected to one end of said bridge and provided with tracks forming an extension of the bridge tracks when the boom is in horizontal position, a wheeled trolley, means for traversing said trolley on said tracks, a material receiving bin mounted on one of said legs and adapted to receive the material being transferred, said bin accommodating the bucket when the boom is raised for handling general cargo.

ERNEST W. TAYLOR.
